(57) **CLAIM**

The ornamental design for a LED lighting, as shown and described.

DESCRIPTION

FIG. 1 is a front perspective view of a LED lighting showing my new design;

FIG. 2 is a rear perspective view thereof;

FIG. 3 is a front elevational view thereof;

FIG. 4 is a left side elevational view thereof;

FIG. 5 is an enlarged top view thereof; and,

FIG. 6 is an enlarged bottom view thereof.

The broken lines in the drawings illustrate portions of the LED Lighting which forms no part of the claimed design.
